HOSE NOZZLE

Robert A. Gilmour, Somerset, Pa., assignor to Gilmour
Manufacturing Company, a division of R. M. Smith,
Inc., Somerset, Pa.

Filed Dec. 21, 1970, Ser. No. 26,599

Term of patent 14 years

Int. Cl. D23—01

U.S. Cl. D23—34

Fig. 1

Fig. 2

Fig. 3

FIG. 4

FIG. 5

FIG. 6

FIG. 1 is an elevational view taken from one side of a hose nozzle embodying my new design;

FIG. 2 is a top plan view thereof;

FIG. 3 is a front elevational view thereof;

FIG. 4 is an elevational view taken from the side opposite that shown in FIG. 1;

FIG. 5 is a rear elevational view thereof; and

FIG. 6 is a bottom plan view thereof.

I claim:

The ornamental design for a hose nozzle, as shown.
